UNITED STATES PATENT OFFICE.

GEORGE H. GROUNDS, OF CHICAGO, ILLINOIS.

AIR-VALVE FOR GAS-ENGINES.

1,299,571.

Specification of Letters Patent.

Patented Apr. 8, 1919.

Application filed April 20, 1918. Serial No. 229,796.

To all whom it may concern:

Be it known that I, GEORGE H. GROUNDS, a citizen of the United States, and a resident of the city of Chicago, county of Cook, and 5 State of Illinois, have invented certain new and useful Improvements in Air-Valves for Gas-Engines, of which the following is a specification.

My present invention has relation to the 10 provision of simple and effective means for admitting air to the fuel manifold of an internal combustion engine in such quantities as may be found necessary to secure as complete a combustion as possible of the fuel. 15 I am aware that the ordinary makes of carburetors at present upon the market have both manually adjustable and automatic instrumentalities for graduating the amount of fuel and air supplied to the cylinders of an 20 internal combustion engine, but, because of wear in use and also because of an initial failure to secure a proper adjustment, it is not at all uncommon and, in fact, it is the general rule that the charges received by the 25 engine cylinders are improperly proportioned in fuel and air.

As will be seen from the following specification, my present device is auxiliary to the carburetor and is designed to be attached to 30 the fuel intake manifold which distributes the charge from the carburetor to the cylinder, or cylinders if a plurality of cylinders are employed, of the integral combustion engine. By reason of the positioning of my device 35 between the carburetor and the cylinder or cylinders, the adjustment and operation or functioning of any particular portion of the carburetor is not interfered with directly, and, again, when hot air is used in the carburetor to assist in vaporizing the fuel, the 40 additional amount of air admitted through my device may be entirely unheated, which will assist in keeping the cylinders cool without interfering with the vaporization of the 45 fuel which takes place in the carburetor. It will be readily appreciated that such a device must contain or comprise means for nicely and accurately controlling the amount of air so introduced.

50 The objects of my invention are the provision, in as simple a form as possible, of means for securing the introduction of fresh air to the fuel intake manifold of an internal combustion engine; means for accurately regulating the amount of air so introduced; 55 means for positively locking the adjustment

of the device so that the severe vibrations incident to the operation of internal combustion engines and, especially, when such an engine is used in a motor vehicle on ordinary 60 roads, will not disturb the adjustment; and means for positively closing the device and discontinuing its operation entirely when atmospheric and other conditions permit of its use being so discontinued. 65

I prefer to accomplish the divers objects of my invention by substantially the means and in the manner hereinafter fully described and as more particularly pointed out in the claims, reference now being had to the 70 accompanying drawings forming a part of this specification, in which,—

Figure 1 is a side elevation of a preferred form of my device, enlarged somewhat for clearness from a size suitable for engines employed in motor vehicles.

Fig. 2 is a central section of the form shown in Fig. 1, the section being taken on line 2—2, of Fig. 3.

Fig. 3 is a transverse or cross-section there- 80 of taken on line 3—3, of Fig. 2.

Referring to the drawings, in which similar reference characters are employed to designate the same parts throughout the divers views, it will be observed my device 85 preferably comprises a hollow or tubular stub 5, one end whereof is provided with a slightly tapered exteriorly threaded portion 6 which is adapted to be screwed into a suitably tapped aperture provided in the intake 90 or fuel manifold of an internal combustion engine. Above the threaded portion 6 just referred to, is an annular enlargement 7, of preferably hexagonal conformation in transverse section, to facilitate the use of a 95 wrench thereon when introducing and assembling the device with the threaded aperture in the manifold. Above the annular enlargement 7, the stub 5 is cylindrical in shape and exteriorly threaded at 8 to the 100 end thereof, and in its periphery are provided the semiconical or tapered channels 9, increasing in depth from their points of commencement near the enlargement 7 to the outer or upper end of the cylindrical por- 105 tion of the stub.

An interiorly threaded washer 10 is provided that is adapted to screw down on the threads on the cylindrical portion, and the threads 8 of the cylindrical portion are cut 110 away at 11 adjacent the enlargement 7, so that the washer 10 will be free from threaded

engagement when it is adjacent said enlargement. An interiorly threaded tubular cap 12 screws down over the threads 8 of the cylindrical portion. It will now be seen that 5 the positioning of the washer 10 and the cap 12 longitudinally with respect to the tapered channels 9 will permit of a fine adjustment of the capacity of the openings provided by the said channels 9, and the 10 amount of air entering therethrough, and that any intermediate positioning of the cap 12 may be locked positively by turning back the washer 10 so as to frictionally engage or jam the lower edge of the cap. If 15 it is desired to entirely close the device, the threaded washer 10 is turned down until it leaves the threads 8 and is positioned upon the upper portion of the enlargement 7, whereupon the cap is screwed down until 20 it jams tightly against said washer, thereby closing the tapered channels 9 in the cylindrical portion and preventing any air being admitted to the device therethrough.

While I have herein illustrated and 25 described certain specific instrumentalities for carrying out my invention, it of course will be obvious to others skilled in the art, that divers modifications and alterations may be made without materially departing from 30 the spirit of my invention. I therefore desire it understood that all such changes are contemplated as being included within the scope of my invention as expressed in the appended claims.

35 What I claim is:—

1. An air valve for gas engines comprising a tubular threaded stub that is provided upon its exterior with a plurality of semiconical channels extended longitudinally of said stub and open at the end of 40 said stub, an interiorly threaded cap co-operating with the threads of said stub to control the cross-sectional capacity and operative length of said semiconical channels, 45 and a threaded lock washer adapted to co-operate respectively with said stub and said cap.

2. An air valve for gas engines comprising a tubular threaded stub that is provided upon its exterior with a channel extended longitudinally of said stub and open

55 at the end of said stub, an interiorly threaded cap co-operating with the threads of said stub to control the operative length of said channel, and a threaded lock washer adapted to co-operate respectively with said stub and said cap.

3. An air valve for gas engines comprising a tubular threaded stub that is provided upon its exterior with a channel extended longitudinally of said stub of progressively increasing depth, an interiorly threaded cap co-operating with the threads of said stub to control the cross-sectional capacity and operative length of said channel, and a threaded lock washer adapted to co-operate respectively with said stub and said cap.

4. An air valve for gas engines comprising a tubular stub, a central enlargement having an angular conformation, an annular groove surrounding said stub adjacent said enlargement, threads provided on said stub between said groove and the 75 end of said stub, said threaded portion having a progressively increasing longitudinally disposed channel therein, a threaded washer co-operating with said threads and of a width to be accommodated by said groove, and an interiorly threaded cap 80 adapted to co-operate with the threads of said stub and said washer.

5. An air valve for gas engines comprising a tubular stub, a central enlargement having an angular conformation, an 85 annular groove surrounding said stub adjacent said enlargement, threads provided on said stub between said groove and the end of said stub, said threaded portion having a plurality of progressively increasing 90 longitudinally disposed channels therein, a threaded washer co-operating with said threads and of a width to be accommodated by said groove, and an interiorly threaded cap 95 adapted to co-operate with the threads of said stub and said washer.

Signed at Chicago, county of Cook and State of Illinois, this 9th day of March, 1918.

GEORGE H. GROUNDS.

Witness:

H. SLACK.
